UNITED STATES PATENT OFFICE.

JEAN PAUL LE GRAND AND NARCISSE CHENEAU, OF LEVALLOIS-PERRET,
FRANCE.

RESILIENT TIRE.

SPECIFICATION forming part of Letters Patent No. 716,066, dated December 16, 1902.

Application filed January 15, 1902. Serial No. 89,813. (No model.)

To all whom it may concern:

Be it known that we, JEAN PAUL LE GRAND and NARCISSE CHENEAU, manufacturers, citizens of the Republic of France, residing at 9 5 Rue Danton, Levallois-Perret, Seine, France, have invented certain new and useful Improvements in Resilient Tires, of which the following is a specification.

Our present invention has relation to an 10 improved form of distending means for elastic tires which may be used either in connection with the pneumatic tubes commonly employed, in which case they serve to protect the tire from damage when not inflated, or it 15 may be employed alone with a proper exterior envelop and without the air-tube.

It has been hitherto proposed to employ chaplets of more or less elastic masses strung on a cord or the like within the outer envelop 20 for the purposes above indicated; and our present invention has relation to improvements in this class of device whereby the masses in question are prevented from slipping along the cord and being jammed together under the influence of a sudden stop 25 caused by severe application of the brake or otherwise.

One important branch of this invention has relation to a novel means whereby the degree 30 of resilience of the separate masses employed may be regulated at will without having recourse to changes in the composition of the rubber, which latter expedient necessarily causes deterioration in the quality of the material.

One form of our invention is illustrated in the accompanying drawings, wherein—

Figures 1 to 3 are longitudinal sections of a portion of hollow tires provided with different forms of our improvement, and Fig. 4 is a perspective view of a portion of one form of hollow tire provided with our improved chaplet.

In Fig. 1 the outer tube is shown at 1, and 45 at 2 are shown hollow balls, of rubber or similar elastic material. These balls, together with the intermediate spools 3, are strung upon a central cord 4, which may be of any desired construction. In our claims this element is claimed as a "cord;" but it is to be understood that this term covers any of the

well-known equivalents for cord or string. Each intermediate body 3 is fixed in place upon the central cord by a pin or bolt 5. These bodies are made of wood or other relatively non-elastic and hard material, and they serve to prevent the balls 2 from coming in contact or slipping along the chaplet. Within each ball 2 is a hard spool 6 with a concave outer surface, also strung upon the central 55 cord. The object of this core 6 is to limit the degree of compression of the ball 2 when under weight. In operation the balls will first collapse and will then be compressed upon their cores. The relative degree of collapse and 60 compression can be easily controlled by the form and relative size of each core.

In the preferred form (shown in Fig. 1) the spools 3 have necks 7, which enter openings at the two sides of each ball 2, serving to support the edges of said openings, as well as to provide an abutment for each ball to prevent its slipping.

In Fig. 2 the core within the ball 2 is shown at 8 as being cylindrical in shape. This is to 75 illustrate the variety of forms which may be given to this core without departing from our invention.

The form shown in Fig. 3 is particularly useful where the tire is to be applied to wheels 80 designed to carry heavy loads. Here each ball 2 is replaced by an annular mass 9 of rubber or the like, within which is a core 10, which entirely fills the opening thereof. In order that when the core is in place it may 85 act to compress the rubber 9 and limit its further compression under load, we prefer to make the inner core 10 of a diameter greater than the normal inner diameter of the mass 9 when not surrounding the core.

Fig. 4 shows a portion of one form of outer envelop which may be applied to our improved chaplet; but we are not to be limited to this or any other one form of outer envelop in this connection.

The advantage of our construction is that the intermediate spools or bodies 3, being fixed to the central cord, prevent movement of the balls among themselves under any circumstances and prevent these balls or other bodies 100 from piling and jamming the one on the other when a sudden stop occurs.

What we claim is—

1. A hollow tire containing a chaplet composed of a central cord, elastic bodies strung thereon at intervals, hard bodies also strung thereon between successive elastic bodies to keep the latter apart and means for fixing said hard bodies in place on said cord, substantially as and for the purposes described.
- 5 2. A hollow tire containing a chaplet comprising elastic bodies consisting of a perforated mass of elastic material and a core of hard material surrounded thereby, said core

having a diameter greater than the normal diameter of the perforation in said elastic mass, substantially as and for the purpose 15 described.

In witness whereof we have hereunto signed our names, this 14th day of November, 1901, in the presence of two subscribing witnesses.

JEAN PAUL LE GRAND.
NARCISSE CHENEAU.

Witnesses:

PAUL TOURNOL,
WALTHER HARTMANN.
